EMIL S. GRAFENSTATT, OF LOS ANGELES, CALIFORNIA

DEEP-WELL PUMP

Application filed March 10, 1926. Serial No. 93,576.

This invention relates to deep well pumps such as used for raising oil or water.

It is common practice to employ a reciprocating pump rod operated from the mouth 5 of the well and carrying a plunger at the level of the oil at the bottom of the well. In deep wells, the weight of this pump rod is considerable and causes a considerable elongation of the rod in the up-stroke of the 10 plunger. This detracts from the efficiency of the pump and is one of the objections inherent in pumps of that type.

It has been attempted to avoid the use of reciprocating pump rods in deep wells by 15 employing pumps operating on the air-lift principle but the objection to pumps of that type is that if the well is very deep, the air or gas used for producing the "air lift" must be at a relatively high pressure, and in the 20 use of the high pressure air, there is a tendency for the suction developed at the foot of the flow pipe to cause an inflow of the oil sand into the casing.

The general object of this invention is to 25 overcome these difficulties and to provide a pump of simple construction which can be placed at a low level in the well casing and which will be operated automatically through the agency of fluid or liquid under 30 pressure. Such pressure may be maintained in the casing, that is to say in the space surrounding the flow-pipe. One of the objects of the invention is to produce a pump of this type which will operate to raise the water 35 or oil on both strokes of the pump.

Another object is to provide a deep well pump employing but one pipe within the well casing for embracing the pump and control valve mechanisms.

40 Another object is to provide a device in which only a single valve is necessary to control the operation of the pump.

A further object is to provide a deep well pump including a tubular plunger having 45 a power head, and carrying a check valve, together with a fixed sleeve within the pump barrel which telescopes within the plunger, and an assembly so designed that the velocity of the column from the well toward the 50 pump, and the velocity of the column from

the pump toward the outlet will be the same on the up and down strokes of the plunger.

A still further object is to provide a pump including a control valve which will at no time stop or retard the movement of oil from 55 the well toward the outlet.

A further object is to provide a pump mechanism so arranged that a renewal of the check valve in the upper end of the barrel, and also of the check valve carried on the 60 plunger will be effected without disturbing the position of the barrel in the well.

A still further object is to provide a pump whereby the fluid from the well may pass 65 through the pump without coming in direct contact with the power head or the walls of the pump cylinder.

Another object is to provide a pump in which the mechanism is so arranged that a reversal of the control valve position may 70 be initiated at points near the completion of each stroke, before the piston reaches the corresponding end of the pump cylinder.

Further objects of the invention will appear hereinafter.

The invention consists in the novel parts and combinations of parts to be described hereinafter, all of which contribute to produce an efficient deep well pump.

A preferred embodiment of the invention 80 is described in the following specification, while the broad scope of the invention is pointed out in the appended claims.

In the drawing:

Figure 1 is an ideal vertical section 85 through the casing and flow-pipe of a well provided with a pump embodying my invention. This view shows the controlling valve for the pump in its extreme low position; in this view, parts of the pump are 90 shown partly in elevation and broken away.

Figure 2 is a view similar to Figure 1 but is a section taken on the line 2-2 of Figure 1, looking toward the left, certain 95 parts of the pump, including the pump plunger, being shown partially in elevation and broken away.

Figure 3 is a cross-section through the casing and pump, taken about on the line 3-3 of Figure 1, and particularly illustrat- 100

ing the arrangement of the ports or passages through which the liquid being pumped passes during the operation of the pump.

Figure 4 is a cross-section through the casting and pump taken about on the line 4—4 of Figure 1 and particularly illustrating the construction in the vicinity of the controlling valve.

Figure 5 is a view similar to Figure 4, 10 but taken at the level of the line 5—5 of Figure 1.

Figures 6 and 7 are longitudinal sections broken away and illustrating the construction of the full length of the casing of the 15 well, in which connection it should be understood that Figure 7 shows the apparatus at a level below the parts shown in Figure 6.

Figure 8 is a vertical section taken through the casing and flow-pipe, certain 20 parts being broken away and showing the valve substantially at the upper end of its stroke.

Figure 9 is a vertical section similar to Figure 8 but showing the valve in an intermediate position; this view is upon an enlarged scale.

Figure 10 is a view showing the same 30 parts illustrated in Figure 9, but is a vertical section taken on the line 10—10 of Figure 9, looking toward the left.

In the drawing, 1 represents the usual well casing within which the flow-pipe 2 is located. In applying my invention, I provide means for delivering fluid under pressure at the bottom of the well. In order to do this I prefer to provide a packing head 3 which packs off the upper portion of the casing so as to form an annular pressure chamber 4 between the casing and the flow-40 pipe.

The pump includes a casing 5, the lower portion of which has a threaded connection with the flow-pipe 2 and the upper portion of which is formed into a pump barrel 45 6 within which a plunger 7 reciprocates. This plunger is of tubular form, its lower end being slightly enlarged to form a collar 8 which constitutes the head of the plunger. The body 9 of the plunger is of tubular 50 form and extends upwardly from the head 8, and at its upper end is provided with a suitable check valve 10 which may be of the ball type illustrated.

In the operation of the pump, the oil 55 flows upwardly through the bottom head 11 of the barrel and flows through an inner tube or bushing 12, the lower end of which is secured in the opening through the bottom head 11 of the pump.

Within the upper end of the barrel, a 60 sleeve 12^a is secured, for example, by set-screws 13, and the annular space 14 between the lower end of this sleeve and the head 8 constitutes the cylinder space or 65 chamber of the pump barrel.

It should be understood that in the pressure chamber 4, I maintain a fluid or liquid under pressure. The flow of this fluid to the pump is controlled automatically by a valve 15; this valve is preferably mounted coaxially on the plunger; and I prefer to control the operation of the valve 15 through the medium of the pump plunger, that is to say, at the end of each stroke of the pump plunger, it automatically sets the valve in an opposite position which will reverse the direction of the movement of the pump plunger.

In order to accomplish this, I provide a tail-rod 16 which extends down through the inner sleeve 12 and through the opening in the lower head 11 of the pump. This tail-rod is secured at its upper end in a spider 17 which is carried at the upper end of the plunger. I use a spider at this point so that it will provide ports or openings 18 through which the fluid being pumped can pass upwardly in moving past the valve 10.

The ports which control the operation of the plunger and of the valve 15 are formed 90 in the wall of pump casing.

While the valve 15 is thrown automatically toward a reverse position by the pump plunger at the end of its stroke, I provide means controlled by the pressure in the pressure chamber 4 to control the valve 15, further; this prevents stopping of the pump in some intermediate position from which it might fail to start when the pressure in the pressure chamber 4 was resumed. In the 100 operation of the pump the plunger initiates the movement of the valve and the fluid pressure completes the movement and holds the valve in its opposite position. In order to accomplish this I provide the lower end of the valve 15 with an operating piston 19 which has two large heads 20 and 21 connected by a waist 22 of reduced diameter. The valve 15 is also of piston type and includes a lower head 23, an intermediate head 24 and an upper head 25. These heads all co-operate with ports to control the flow of the fluid in the operation of the pump.

In Figure 1, the valve 15 is shown in its extreme low position, at which time the pressure chamber 26 (which forms the upper end of the cylinder in which the valve 19 reciprocates), is supplied with fluid under pressure through a port 27 which communicates with the pressure chamber 4. The pressure on the upper end of the head 20 will therefore hold the valve 19 down in its extreme low position.

When the plunger 7 arrives at the end of its upstroke, the tail-rod 16 will pull the valve 15 up toward its elevated position. In order to accomplish this, I prefer to provide the lower end of the tail-rod 16 with a coil spring 28; during this stroke, the upper end of this spring strikes a spider 19^a which 125

is formed in the lower end of the piston 19 and exerts force upon the piston and valve 15 to raise the same. This will effect an upward movement of the valve during the first part of which fluid in the pressure chamber 26 will be forced back through the port 27 into the pressure chamber 4. Eventually, however, the head 20 of the piston 19 will close this port 27, (see Figure 9), but when this occurs, the liquid within the pressure chamber 26 can flow around a by-pass port 28 around the head 20 and around the waist 22 of the piston 19 so as to escape through an outlet port 29. This port is in communication with a passage 30 that extends upwardly in the wall of the barrel and communicates with the flow-pipe above an upper check valve 31 (see Figure 7), located at the upper end of the pump.

As the upward movement of the piston 19 progresses, the lower head 21 eventually uncovers a port 32 which opens communication between the lower pressure chamber 33 and the pressure chamber 4 and admits the fluid under pressure to the under face of the lower head 21. This moves the piston 19 and valve 15 positively up to its extreme upper position.

At the end of the down-stroke of the plunger, the valve 15 and piston 19 are started in their downward movement by a spring 34, (see Figure 1), which is similar to the spring 28 and which seats on shoulder 35 on the tail-rod. This spring 34 strikes against a spider 36 at the upper end of the valve 15 and moves the valve and piston 19 down until the head 21 closes the port 32. As soon as this port 32 is closed by the head 21, a by-pass passage 37, similar to the by-pass 28, is opened and this permits the fluid in the chamber 33 to flow around the waist of the piston 19 and through the outlet port 29.

When the piston is moved by the springs 45 they have considerable energy stored up in them, and it is this energy in the spring which carries the piston and valve past the neutral position of the piston when the port communicating with the pressure chamber 14 becomes closed.

When the valve 15 is in its closed position, as indicated in Figure 1, the fluid in the pressure chamber 4 flows in through an inlet port 38 around the lower waist 39 of the valve through a port 40 in the side of the valve chest and up a passage 41 which communicates with the lower pressure chamber 42 of the pump barrel. This forces the pump plunger 7 upwardly, and the spent fluid in the space 14 passes out through a passage 43 and through a port 44 into the valve chest where it passes out through an outlet port 45 which communicates with the passage 30 already described.

Near the end of the up-stroke of the

plunger, the spring 28 initiates the upward movement of the piston 19 which is co-operated with by the fluid pressure of the port 32 to complete the upward movement of the valve 15.

In Figure 8, the valve 15 is illustrated in its extreme uppermost position; this connects the parts in a reversed manner. The arrows in that figure indicate that at this time the upper waist 46 of the valve is in position to permit inward flow of the fluid under pressure through port 47; the fluid, after passing the valve passes up the passage 48 to drive the plunger down, and in this position of the valve, the intermediate head 24 is above the port 45 which places this port in communication with the port 40; this will permit fluid to flow into the valve chamber from the passage 41 and through the port 45 into the passage 30 through which the fluid passes upwardly so that it is discharged into the flow-pipe 2 above the upper valve 31, (see Figure 7).

In operation, as shown in Fig. 2, with the plunger at the lower end of its stroke, the control valve is also in its lowermost position in the valve chamber, and is so held by pressure entering through port 27, so that fluid may enter through port 38 around waist 39 of the valve, and thence through port 40 and passage 41 to the lower end of the power head 8. Thus, plunger 9 is forced upwardly, thereby forcing fluid above the check valve 10 on through the fixed valve 31 to the flow pipe.

On this up-stroke of the plunger 8 the fluid from the power chamber 14 above the head 8 is expelled through passage 43 and port 44 to the valve chamber and around the waist of the control valve, and thence through port 45 to passage 30, from which it is discharged into the flow pipe above the valve 31. As plunger 8 nears the end of the upstroke the spring 28 carried on the valve rod 16 engages the control valve and serves to initiate the movement thereof upwardly, thus expelling the fluid from above the power head 20 of the valve, through port 27 to the pressure area, and this movement of the plunger and valve continues until the part 23 of the valve laps port 38 from the pressure area, the portion 24 thereof laps port 45 to the flow pipe, and the portion 20 laps port 27 to the pressure area.

In this intermediate position of the control valve the ports 28 and 37 are in communication with the port 29 to passage 30, thereby balancing the operation of the valve. A further upward movement of the control valve is effected by means of the energy stored up in the spring 28 on the plunger rod. Thus, port 32 to the pressure area is opened and port 37, which permitted communication with the flow pipe is closed.

Fluid under pressure may now enter port 32 below portion 21 of the control valve to move the control valve upwardly to the end of its stroke, in which extreme position the port 38 is lapped by the portion 23 of the valve, and port 47 is open to communication with port 44 and passage 43, so as to permit fluid to flow through said passage under pressure, to the upper face of the power head 8. The plunger is thereby forced downwardly by pressure and fluid is expelled by the lower face of plunger 8 from chamber 42, through passage 41 and port 40 to the valve chamber, around the waist 39 of the control valve, and thence through port 45 into the passage 30, from which it is discharged into the flow pipe at a point above the check valve 31.

The downward movement of the plunger continues until the spring 34 carried by the valve rod 16 engages the upper end of the control valve for forcing said valve downwardly, thereby expelling fluid from the lower face of the power head 21 of said valve through port 32 to the pressure area until port 32 is closed. In this intermediate position of the control valve ports 27 and 32 are closed and ports 28 and 37 are in communication with port 29 to passage 30, thereby balancing the pressures on the valve. The energy in spring 34 thus acts to further move the valve downwardly, closing port 28 and opening port 27, admitting fluid under pressure to the upper face of the power valve through port 27, to force the valve downwardly to the end of its stroke, where it is held in position preparatory to another operation.

The fluid in the well will at all times fill the control valve and plunger 9, and will rise through valve 10 and 31 into flow pipe 2.

It is understood that the embodiment of the invention described herein is only one of the many embodiments this invention may take, and I do not wish to be limited in the practice of the invention, nor in the claims, to the particular embodiment set forth.

50 What I claim is:

1. In a deep well pump, the combination of a well casing with a flow-pipe within the same, a pump barrel connected into the flow-pipe, said casing being arranged for maintaining a pressure zone therewithin and externally of the flow pipe, a connection to the well casing for supplying fluid under pressure to the pressure zone, a plunger within the pump barrel, check-valves cooperating with the same to enable the plunger to raise liquid, said barrel having ports for opening communication to the pressure zone, a valve chamber, and passages connecting the valve chamber with opposite portions of the pump

barrel, and a control valve below the plunger for controlling the flow of the fluid through said ports and passages, from the pressure zone to both ends of the pump barrel, the fluid pressure operating to move the plunger in opposite directions. 70

2. In a deep well pump, the combination of a well casing, a flow-pipe within the same, a pump barrel connected into the flow-pipe, means for maintaining a pressure zone within the casing externally of the flow pipe, a connection to the well casing for supplying fluid under pressure to the pressure zone, a fixed sleeve within the pump-barrel communicating at its ends with the flow pipe so as to pass the liquid up through the pump barrel, a tubular plunger telescoping with the fixed sleeve and having a head in the annular space between the wall of the barrel and the fixed sleeve, check-valves 85 cooperating with the plunger to enable the same to raise liquid, said barrel having ports for opening communication to the pressure zone, a valve for controlling the opening and closing of said ports to apply pressure to said plunger, means for actuating the valve by the plunger, and means permitting the exhaust of the contents of the well through the pump plunger. 90

3. In a deep well pump, the combination of a well casing, a flow-pipe within the same, a pump barrel connected into the flow-pipe, said casing operating as a pressure chamber around the flow pipe, a connection to the well casing for supplying fluid under pressure to the pressure chamber, a fixed sleeve within the pump-barrel communicating at its ends with the flow pipe so as to pass the liquid up through the pump barrel, a tubular plunger telescoping with the fixed sleeve and having a head in the annular space between the wall of the barrel and the fixed sleeve, check-valves cooperating with the plunger to enable the same to raise liquid, said barrel having ports and passages for opening communication to the pressure chamber and to the barrel, a valve for controlling the opening and closing of said ports and passages, means for actuating the valve by the plunger, and by the fluid 110 under pressure in the pressure chamber, for controlling the flow of the fluid from the pressure chamber to the pump-barrel, and means permitting the exhaust of the contents of the well through the pump plunger. 115

4. In a deep well pump, the combination of a well casing with a flow pipe within the same, a pump barrel connected into the flow pipe, a pressure chamber being maintained within the casing around the flow pipe, a connection to the well casing for supplying fluid under pressure to the pressure chamber, a fixed sleeve within the pump-barrel operating to pass the liquid moving upwardly through the pump, a tubular plun- 120 125 130

ger telescoping with the sleeve and having a head to move within the pump barrel, check-valves cooperating with the plunger to enable the plunger to raise liquid, a valve chamber below the barrel, said valve-chamber having ports leading to it from the pressure chamber and said pump barrel having ports leading to it from the valve chamber, a valve within the valve chamber, means for controlling the valve by the plunger at the ends of the stroke to enable the valve to control the flow of the fluid from the pressure chamber to the pump barrel, and means for exhausting the contents of the well through the pump plunger.

5. In a deep well pump, the combination of a casing with a flow-pipe within the same, a pump barrel connected into the flow-pipe, a pressure chamber being maintained within the casing for supplying fluid under pressure to the pressure chamber, a fixed sleeve within the pump barrel operating to pass the liquid upwardly through the same, a tubular plunger telescoped with the sleeve and having a head arranged to move in the pump barrel, a fixed check-valve carried by the plunger, said pump barrel having a port leading to the flow pipe above the fixed check valve and having ports for supplying operating fluid to the ends of the pump barrel, a valve-chamber below the pump-barrel, a valve mounted therein for controlling communication between the valve chamber and the pressure chamber, means for controlling the said valve by the fluid from the pressure chamber, and means permitting the discharge of the output through and above said plunger into said flow pipe.

6. In a deep well pump, the combination of a casing with a flow-pipe within the same, a pump casing with a barrel connected into the flow pipe, a pressure chamber within the casing around the flow pipe, a connection to the well casing for supplying fluid under pressure to the pressure chamber, a fixed sleeve within the pump-barrel operating to pass the liquid upwardly through the same, a tubular plunger telescoped with the sleeve and having a head to move in the pump barrel, check-valves cooperating with the plunger to enable the same to raise liquid through the flow pipe, a valve chamber and an adjacent pressure chamber within the pump casing below the barrel, a valve in the valve chamber and a controlling piston for the same in the last named pressure chamber, said plunger having a tail-rod extending down through the said valve and the said piston, with means for engaging the valve to shift the same near the end of the stroke of the plunger, said barrel having ports leading from the valve-chest and controlled by the said valve for operating the plunger, said valve-chest having ports communicating with the first named pressure

chamber and also having ports for admitting the fluid from the first named pressure chamber to the ends of said second named pressure chamber, and means above said plunger for permitting the discharge of the output through said plunger into said flow pipe.

7. In a deep well pump, the combination of a casing with a flow-pipe within the same, a pump casing with a barrel connected into the flow-pipe, means for maintaining a pressure chamber within the casing around the flow pipe, a connection to the well casing for supplying fluid under pressure to the pressure chamber, a plunger mounted to reciprocate within the barrel, check-valves cooperating with the plunger to enable the same to pump liquid through the flow pipe, a valve chamber below the barrel, a piston-valve mounted to reciprocate therein having an upper head, a lower head, and an intermediate head with waists between said heads, said barrel having a port for admitting fluid under pressure from the valve chamber to one end of the pump barrel and

another port for admitting fluid under pressure to the other end of the pump barrel from the valve-chest, said pump casing having a pressure chamber with a piston moving within the same and attached to the piston-valve, and having ports communicating with the first named pressure chamber for controlling the operation of the piston-valve, said valve-chamber having ports communicating with the first named pressure chamber, the said heads of said piston valve cooperating with the last named ports and the first named ports to control the flow of the fluid under pressure to the barrel to actuate the plunger, and means permitting the discharge of fluid through said plunger into said flow pipe.

8. In a deep well pump, the combination of a casing with a flow-pipe within the same, a pump casing with a barrel connected into the flow-pipe, means for maintaining a pressure chamber within the casing around the flow pipe, a connection to the well casing for supplying fluid under pressure to the pressure chamber, a fixed sleeve within the pump-barrel operating to pass the liquid upwardly through the same, a tubular plunger telescoped with the sleeve and having a head to move in the pump barrel, check-valves cooperating with the plunger to enable the same to raise liquid through the flow pipe, a valve-chamber and an adjacent pressure chamber within the pump casing below the barrel, a valve in the valve chamber and a controlling piston for the same in the last named pressure chamber, said plunger having a tail-rod extending down through the said valve and the said piston, with means for engaging the valve to shift the same near the end of the stroke of the plunger, said barrel having ports leading from the valve-chest and controlled by the said valve for operating the plunger, said valve-chest having ports communicating with the first named pressure

the stroke of the plunger, said barrel having ports leading from the valve-chest and controlled by the said valve for operating the plunger, said valve-chest having ports communicating with the first named pressure chamber and also having ports for admitting the fluid from the first named pressure chamber to the ends of said second named pressure chamber, a piston connected with the piston valve, and springs carried on the tail rod for imparting pressure from the tail rod to the piston valve at the end of each stroke of the plunger to initiate a movement of the piston valve to its opposite position, and a discharge valve above and for discharging fluid raised through said plunger.

9. In a deep well pump the combination of a casing and a flow pipe therewith, a pump casing with a barrel attached to the flow-pipe, a plunger within the pump barrel, check-valves cooperating with the same to enable the plunger to raise liquid, a valve chest alined with said barrel co-axial with the plunger, a valve movable within the valve-chest, means for conducting fluid under pressure to the valve-chest, said pump casing having ports leading from the valve-chest to the barrel to operate the plunger and controlled by the valve a tail rod extended from the plunger and operating through said valve, compression springs carried on said tail rod and acting against said valve for mechanically initiating the shifting of the valve toward an opposite position by the plunger at the end of a stroke, and fluid operated means cooperating with the valve for completing the movement of the valve to its opposite position and for holding the same therein, an exhaust outlet being provided above and on said plunger in communication with the flow pipe.

10. A deep well pump comprising a well casing, a pump casing depending thereinto and having a barrel on the lower end thereof, a pressure zone surrounding said barrel and within said well casing, a control valve and a pump piston arranged in opposite portions of said barrel, said barrel having means associated with said valve for regulating the application of pressure to opposite ends of said piston, said pump adapted for connection with a pressure mechanism for maintaining pressure in said pressure zone, and means for discharging fluid from the well through said valve and through said piston into said pump casing.

11. A deep well pump comprising a well casing, a pump casing therewith having a barrel, a plunger and a valve arranged one above the other in axial alinement in said barrel, means for connecting said pump with a pressure mechanism for maintaining an element under pressure in a zone surrounding said barrel and within said well casing, said barrel having means cooperating with

said valve to control the application of pressure to opposite ends of said plunger, an inlet and an outlet being provided in said barrel for effecting a flow of the liquid pumped.

12. A deep well pump comprising a well casing, a pump barrel therein, providing a pressure zone, a flow pipe attached to the upper end of said barrel, a plunger and a valve tandem connected in said barrel, an inlet being provided leading from the casing to said barrel, means for connection with a pressure mechanism for maintaining pressure in said pressure zone, and means associated with said valve for alternately applying pressure to opposite ends of the plunger, and inlet and outlet means permitting the flow of fluid from the well through said plunger and said valve.

13. A deep well pump comprising an inner and an outer pipe, a pumping mechanism embraced within the inner pipe, means for connecting a pressure mechanism with the outer pipe, a control valve within the inner pipe selectively associated with passages through said inner pipe for applying pressure from the outer pipe to opposite portions of the pumping mechanism, an inlet and an outlet for effecting a flow of fluid from the well, and means for discharging the fluid from the well through said valve.

14. A deep well pump comprising an inner and an outer pipe, the outer pipe an inlet pipe and the inner pipe an outlet pipe, a pump plunger embraced within the inner pipe, means for connecting a pressure mechanism in communication with the outer pipe, and a control valve in the inner pipe selectively associated with passages in the inner pipe for regulating the communication between the inner and outer pipes, to direct a pressure element against opposite ends of said plunger, and means for discharging the fluid from the well through said valve and said plunger.

15. A deep well pump comprising an inner outlet pipe, an outer inlet pipe, a plunger within the inner pipe, a pressure element being adapted to be held in the outer pipe, means being formed in the inner pipe for affording communication between the inner and outer pipes, an inlet and an outlet being provided for effecting a flow of fluid from the well, a control valve operably connected with said plunger and within the inner pipe for controlling communication between said pipes and the application of said pressure element to said plunger, and means for discharging fluid from the well through said valve and said plunger.

16. A deep well pump comprising a well casing, a single pipe depending thereinto forming a discharge for the well, a pump barrel attached thereto having alined pump and valve chambers arranged for communication with said casing, an inlet and an

outlet for the well fluid, a plunger in the pump chamber, a control valve in the valve chamber, ports and passages being provided in the barrel and adapted for opening and closing by said valve to apply pressure to opposite ends of said plunger alternately, and means extending through said plunger and yieldably connected with said valve for initiating a reverse movement of said valve near the end of each stroke thereof.

17. A deep well pump comprising a well casing, a single pipe therein forming a discharge from the well, a barrel attached thereto having an inlet and an outlet for the well fluid, a plunger rod extending through said barrel and provided with a valve at its upper end, a piston in said barrel embracing said rod, a control valve in said barrel below said piston, said barrel having ports and passages therein adapted to be opened and closed by said valve for applying pressure from said casing to opposite ends of said plunger, alternately at each stroke of the pump, and means on said rod at the ends of said control valve for initiating the reverse movement thereof near the ends of each stroke of said piston.

18. A deep well pump comprising a well casing, a flow pipe therein having a pump barrel attached thereto, having an inlet and an outlet for the well fluid, separate pump and valve chambers in said barrel, a piston in the pump chamber, a control valve in the valve chamber, means for connecting a pressure mechanism with and for maintaining a fluid under pressure in said casing, an inlet being provided from said casing to, and for admitting said fluid to, said valve chamber, and passages being provided in said barrel connecting said valve chamber with opposite portions of said pump chamber, for directing said pressure fluid to and exhausting the same from opposite portions of said piston.

45. 19. A deep well pump comprising a well casing, means for connecting a pressure mechanism therewith for maintaining a fluid under pressure therein, a flow pipe in the casing having a pump barrel provided with alined pump and valve chambers, ports being provided for affording communication between said valve chamber and said casing, a hollow piston in said pump chamber, a control valve in said valve chamber below said pump chamber, passages being formed in said barrel for directing pressure from said casing through the valve chamber to opposite ends of said piston, and means for discharging the contents of the well on the up-stroke of the piston through said valve chamber into said flow pipe.

60. 20. A deep well pump comprising an inner and an outer pipe, axially alined chambers in the inner pipe, a concentric sleeve in one of said chambers, a pump piston em-

bracing said sleeve, a control valve in the other chamber for regulating communication between the outer pipe and the valve chamber, said outer pipe adapted to contain a pressure medium, ports in said inner pipe for transferring said pressure medium from the outer pipe to said valve chamber, passages being provided in said inner pipe leading from the valve chamber to and from opposite ends of said piston, the contents of the well being discharged through said sleeve.

75. 21. A deep well pump including a casing and a pump barrel, tandem arranged plunger and valve means in the barrel, said casing adapted to receive a pressure element, passages being formed in said barrel and controlled by said valve for transferring said element from the casing to opposite ends of said pump at each stroke of the pump, and means connected with and for discharging the contents of the well through said valve and said plunger.

80. 22. A deep well pump comprising a well casing, a pump barrel therein having alined pump and valve chambers, a piston and a control valve in said chambers, respectively, a check valve attached to said piston for controlling the output of the well, a pressure zone between said casing and said barrel, passages being provided through said control valve and said piston through which the fluid in the well is elevated, said barrel having passages controlled by the control valve for applying pressure from the pressure zone to opposite ends of said piston on alternate strokes.

85. 23. In a deep well pump a barrel having alined pump and control valve mechanisms therein, a check valve attached to said plunger for controlling the output of the well, said control valve and said piston arranged to permit the flow of fluid from the well therethrough to said check valve, said barrel having passages therein adapted to be controlled by said control valve for alternately applying pressure to opposite ends of said piston.

90. 24. A deep well pump comprising a barrel, having an inlet and an outlet for the well fluid, a pump chamber being provided therein, a valve chamber being provided therein below the pump chamber, a pumping mechanism within the pump chamber, a valve within the valve chamber, means being provided within the pumping mechanism and within the valve to permit a flow of fluid from the well therethrough, passages provided in said barrel communicating with said valve chamber, and adapted to be opened and closed by said valve for applying pressure to opposite sides of the pump mechanism.

105. Signed at Los Angeles, Calif., this 26th day of February, 1926.
